UNITED STATES PATENT OFFICE.

WILLIAM PETERSON, OF OAKLAND, CALIFORNIA.

FINGER PIECE FOR WRITING INSTRUMENTS.

Application filed January 12, 1924. Serial No. 685,789.

My invention relates to finger pieces or finger grips for pencils and pens and the like articles for writing, for slidably positioning the same on the article where desired for 5 conveniently gripping it to suit one's particular finger-position for writing.

Present devices on the market that I am aware of for this purpose, are for pens only and are fixed thereon and at the pen-point 10 end. This fixed location of the finger piece does not suit all, and is awkward for many and results in one becoming tired of writing soon, or getting the fingers spotted with ink, and if one is a continuous user of the pen, 15 such fixed location of the piece and enforced grip thereof tends to induce writer's cramp and also produces calllosities on the fingers thereat.

I have often seen draftsmen and other 20 constant users of pens, build up a ball of string or rubber bands on some chosen point of the pen for the express purpose of affording a comfortable and cushioning grip thereat, to relieve the tiresomeness of the constant grip 25 and use of the pen.

The objects that I aim to attain are to 30 overcome the above deficiencies by enabling one to purchase, and as a separate article of manufacture, my finger piece and slip the same on the pencil or pen to suit one's most comfortable and efficient writing position.

Another object is to form and make the 35 article of soft material, that will yield to the pressure of the fingers with a cushioning effect for comfortable writing.

Another object is to provide my device 40 with flanges to hold the piece on the pencil wherever it is set, and when the pencil is not in use, the device may be slid to the extreme end of the pencil point, the flange and 45 end of the piece protecting the point from breakage in the pocket or elsewhere.

A further object is to produce the finger 50 piece with ridges or rifles on its exterior for cooling effect in writing.

A further object is to form the device of 55 rubber and of large diameter, so that it may be a substitute for the common pencil or pen clip for holding the pencil or pen in the pocket, the diametrical surface engaging the sides of the pocket and the rubber offering additional resistance to movement.

I attain the above objects by the novel construction of my finger grip, and other objects 55 and advantages of the invention will appear

in the subjoined description of the accompanying sheet of drawings, in which:

Figure 1 is an end view of the invention showing the ridges clearly, and Fig. 2 a side elevation of it, and Fig. 3 a vertical 60 mid-section thereof.

Fig. 4 shows the device in section and applied to a pencil and which may be at any chosen point, and Fig. 5 is a similar view but showing the grip slid down to cover and 65 protect the pencil point as when not in use.

Fig. 6 shows the device positioned on the barrel of a fountain pen and ready for use, and Fig. 7 shows it slid back on the pen cap and serving as a pocket holder, to perform 70 the functions of the common clip for the retention of the pen in the pocket.

Adverting to the drawing and figures thereof: the numeral 8 designates the body of my finger piece and which is preferably 75 formed of a soft, elastic and yielding material, such as rubber, molded ovaliform in shape and of such diameter and length to accomplish the objects sought. To the ends of the body and as part thereof, are inwardly projecting flanges 9 of light thickness, shown to advantage in Fig. 3, having a hole 10 therethrough communicating with the larger bore 11 of the body. The latter bore is usually made smaller than the article 85 the finger piece is intended to encompass for snugly fitting around the same, the flanges 9 serving to elastically bind and hold the piece on the article at the desired location.

12 is an ordinary lead pencil having my 90 device thereon and at a location suitable to many for writing. The flanges 9 are shown to advantage in Fig. 4 in service and binding the finger piece to the pencil.

In Fig. 5 the piece has been slid down to 95 cover the pencil point 13, the lower portion of the body 8 and its flange 9 protecting the said point from injury. The opposite end of the body and its flange 9 is sufficient to hold the piece to and on the pencil.

14 is the barrel of a fountain pen and 15 its cap. The pen has my piece mounted on its barrel in Fig. 6 and in a position suitable for many for gripping and writing. When through writing, and it is desired to use the 105 piece as a substitute for the common pen clip (not shown), the piece may be slipped from the barrel to the cap, as shown in Fig. 7, and when placed in the pocket 16, the pen will be retained therein by reason of the 110

shape of the finger piece and the rifles 17 or other type of grooves or ridges thereon; also the non-slipping property of rubber helps to retain the pen where positioned in the pocket. Of course, a pencil or like article may be supported in the pocket in a similar manner and for a like purpose, and in addition its point will be covered and protected against breakage as shown and described.

10 In operation, one selects the proper finger piece for the article intended and slips the same thereover to any chosen position; the lower flange will always be in proper position on the article as it follows the direction 15 of movement, while the opposite flange will be turned or rolled into the bore for the same reason, but a short stroke of the piece backwards on the article, will cause the said rolled-in flange to assume the proper position as shown in the various figures.

20 What I claim as new and desire to secure by Letters Patent of the United States is the following:

A finger piece for writing instruments, comprising a hollow molded rubber body 25 having a relatively thin transversely projecting internal flange at each end, each flange provided with a small central hole concentric with the hollow of said body, the hollow of said body being of a dimension to contactingly mount the instrument and each flange adapted to turn longitudinally outward on the instrument by a to-and-fro longitudinal movement thereon so as to position and frictionally engage the same in service position, and the said finger piece adapted when not desired in service position to be slid down to the point of the instrument whereby the internal flange thereat will protect the 30 said point, the said body being ovaliform in shape and the said ends thereof equal and similar to render the finger piece reversible whereby either end may be slipped over the instrument.

35 In testimony whereof I affix my signature.
WILLIAM PETERSON.
